United States Patent Office.

STEPHEN S. WILCOX AND ELI J. COLEGROVE, OF LINKLAEN, NEW YORK.

Letters Patent No. 99,042, dated January 18, 1870; antedated January 8, 1870.

IMPROVEMENT IN REVOLVING GRATER.

The Schedule referred to in these Letters Patent and making part of the same.

To all whom it may concern:

Be it known that we, STEPHEN S. WILCOX and ELI J. COLEGROVE, of Linklaen, in the county of Chenango, and State of New York, have invented a new and improved Grater; and we do hereby declare that the following is a full, clear, and exact description thereof, which will enable others skilled in the art to make and use the same, reference being had to the accompanying drawing, forming part of this specification, in which—

Figure 1 represents an end view of our improved grater.

Figure 2 is a vertical longitudinal section of the same.

Similar letters of reference indicate corresponding parts.

This invention relates to a new revolving grater for all kinds of vegetables, and consists in a novel manner of hanging the grater, so that it can be readily taken out of the supporting-frame or vessel, to be cleaned.

The grater A is of cylindrical form, made of perforated sheet-metal, of suitable size, and open at one end, as shown in fig. 2. It is mounted upon a shaft, B, which has its bearings in posts or ears, a b, that project from the ends of a trough or vessel, C.

The post b is, at its lower end, pivoted, by a pin, c, to lugs d d, and can, therefore, be swung out away from the end of the vessel.

A latch, e, is pivoted to the outer face of the post b, and fits into a hook, f, that is fastened to the end

of the vessel C, and projects through an aperture of b, as shown.

When the device is put up for use, as in figs. 1 and 2, the latch is locked into the hook, and thereby retains the post b in a vertical position.

The cylinder A is held above the vessel A C, which is provided with a spout, g, for receiving the articles to be mashed.

The grater is revolved by means of a hand-crank, h, screwed upon the shaft B.

When the grater is to be cleaned, the latch e is unhooked, and the post b swung out, to carry the cylinder into an inclined position, when it can be conveniently cleaned, as its open end is held up.

When the crank is removed, the shaft B, with the cylinder, may be entirely taken off the supports, to be thoroughly cleaned or repaired.

Having thus described our invention,

What we claim as new, and desire to secure by Letters Patent, is—

A cylindrical grater, whose shaft B is hung at one end in a pivoted post, b, which is locked by a latch, e, and hook, as set forth, to allow the ready removal of the grater, substantially as herein shown and described.

STEPHEN S. WILCOX.
ELI J. COLEGROVE.
